UNITED STATES PATENT OFFICE.

WILLIAM HOWARD PAINE, OF PROVIDENCE, RHODE ISLAND, ASSIGNOR TO FIRE PREVENTION COMPANY, A CORPORATION OF RHODE ISLAND.

THERMALLY-CONTROLLED VALVE.

1,142,526.

Specification of Letters Patent.

Patented June 8, 1915.

Application filed January 22, 1914. Serial No. 813,816.

To all whom it may concern:

Be it known that I, WILLIAM HOWARD PAINE, a citizen of the United States, and resident of the city of Providence, in the county of Providence and State of Rhode Island, have invented certain new and useful Improvements in Thermally-Controlled Valves, of which the following is a specification.

10 This invention relates to thermally controlled valves and has for its object to provide a valve of this character that is adapted to be connected in a line of pipe especially for conducting highly inflammable 15 and explosive fluids such as gasoline, illuminating gas and the like, the valve comprising a body portion with a closure operatively mounted therein and normally held in open position by a thermal element in 20 opposition to the tension of a spring. As is well known by those skilled in the art a device of this character must be sensitive and free in its operation, so that even after remaining for a long time without action it 25 will immediately and positively operate as soon as the link is melted. It is found in practice that a packing about the stem of an automatically operating valve is not a practical construction, particularly when the 30 packing is subjected to the deteriorating action of gases, as the natural corroding or roughening of the stem and the disintegrating or softening of the packing, due to the action of the gas upon it, causes the same to 35 cling about the roughened valve stem and so prevent effective action at the time when needed. To obviate this very serious and vital difficulty in valves of this character, I have provided a diaphragm which is made 40 gas-tight and through which the valve is connected to the thermal element. By this construction the uncertainty of action is positively removed as the diaphragm is free at all times no matter how long it has been 45 setting, and will without resistance permit the valve or closure to at once move to its seat as soon as released by the thermal element.

With these and other objects in view, the 50 invention consists of certain novel features of construction, as will be more fully described and particularly pointed out in the appended claims.

Of the accompanying drawings: Figure 55 1— is a central sectional side elevation of

my improved thermally controlled automatic valve showing the same as held in open position by the thermal element in opposition to the spring pressure. Fig. 2—is a central sectional end view through the 60 yoke, diaphragm and upper portion of the valve cap showing the thermal element as having been ruptured and parted and the position of the diaphragm when the valve has moved to closed position. Fig. 3—shows the protecting plate which is located over the diaphragm and to which the yoke is connected. Fig. 4—is a plan view of the diaphragm. Fig. 5—is a sectional side elevation of the same.

Referring to the drawing, 10 designates the body portion of the valve which may be of the ordinary globe type with the inlet at 11 and the outlet at 12, the opening through the bridge being at 13. I have shown a cap 14 as being threaded at 15 to this body, the upper portion of the cap being enlarged and threaded as at 16 on its outer edge to receive a clamping collar 17. The inner portion of this cap is recessed as at 18 to permit the inward stroke of the diaphragm 19. This diaphragm is preferably constructed of thin sheet metal and circularly corrugated at 20 to admit of a sufficient movement to permit the valve or closure to freely move from open to closed position. The plate 21, see Fig. 3, has its center portion 22 removed and its periphery is adapted to rest upon the outer edge of the diaphragm to serve as a stiffening support and receive the direct thrust of the binding collar 17 when clamping the whole together. This plate is provided with a slot 23 on either side through which the shouldered ends 24 of the yoke 25 are passed and riveted for the purpose of supporting the yoke in an upright position. The upper portion of this yoke is bent inward as at 26 and the bent-in portion has a slot 29 to permit the upper end 27 of the link to pass therethrough, which link is locked in position to the yoke by the passing of a pin 28 through its eye 30 to rest in said recessed portion of the yoke.

The upper portion of the link is secured to the lower portion 31 thereof by solder 105 contained in the large opening 32 which solder is adapted to melt or fuse at a very low temperature. If desired a number of small openings may be provided in the links surrounding the main opening 32 to receive 110

solder in order to effect a more rigid connection between the two portions of the link. This is clearly shown in Fig. 1. The lower end of this link is also provided with an eye 33 which is engaged by the hook 34. The lower end of this hook is threaded as at 35 and is screwed into the upper end of the valve stem 36. A lock nut 37 is employed for binding, locking and securing the end 10 of the valve stem to the diaphragm whereby the passing of the stem of the valve through the diaphragm is made gas tight whether the closure is in open or closed position.

15 The lower end of the valve or closure 37 itself, is preferably made tapering so as to fit tightly into its seat when engaging the same, and a spring 38 is coiled about the stem in a recess in the cap, its upper end 20 engaging the shoulder 39 in the recess and its lower end resting upon the head of the closure.

In assembling a valve of my improved construction the closure is placed within the 25 cap with its stem extending through the opening therein. The shank of the hook 34 is then passed through the opening 40 in the diaphragm and screwed into the end of the valve stem. The locking nut is then set up 30 firmly making a tight joint to close this opening 40 in the diaphragm. The yoke, with its plate, is then positioned and the fuse link connected, raising the closure to its open position against the pressure of the 35 spring. It is only necessary now to screw the binding collar 17 tightly down over the plate and the whole of the automatic structure is assembled. The body of the valve is now connected to the cap and the whole is 40 complete, making a device which is positive in its operation and which is sure to act as soon as the heat is applied to the fuse link no matter how long the valve has been in position without having been operated.

45 I claim:

1. A thermally controlled valve comprising a valve casing, a cap removably secured to said casing, a diaphragm forming a closure for said cap, a reinforcing plate 50 mounted upon said diaphragm, a yoke supported by said plate above said diaphragm, a locking ring for securing said diaphragm, reinforcing ring and yoke rigidly to said cap, a valve in said casing, said valve having 55 a stem passing through said cap and said diaphragm, means for rigidly securing said diaphragm to said valve stem, means for

closing said valve, and a fusible link secured to said yoke and said valve stem for normally holding said valve in open position. 60

2. A thermally controlled valve comprising a valve casing, a cap removably secured to said casing, a diaphragm closing said cap, a reinforcing plate disposed upon said diaphragm, said plate being provided with 65 slots at its opposite edges, a yoke supported by said plate and having its ends disposed in said slots, a locking ring for securing said plate, yoke and diaphragm rigidly to said cap, a valve in said casing, said valve 70 having a stem extending through said cap and said diaphragm, means for securing said diaphragm rigidly to said stem, means for closing said valve, and a fusible link connecting said yoke and said stem for holding 75 said valve normally in open position.

3. A thermally controlled valve comprising a valve casing, a cap removably secured to said casing, a diaphragm closing said cap, a yoke supported by said cap, a locking 80 ring for detachably connecting said yoke and diaphragm to said cap, a valve disposed in said casing and having a stem extending through said cap and diaphragm, means for securing said diaphragm rigidly 85 to said stem, a hook removably secured to the inner end of said stem, means for closing said valve, and a fusible link connected at one end to said yoke and its opposite end to said hook for holding said valve 90 normally in open position.

4. A thermally controlled valve comprising a valve casing, a cap removably secured to said casing, a diaphragm closing said cap, a yoke supported by said cap, a locking ring 95 for removably securing said yoke and diaphragm to said cap, the upper end of said yoke being slotted, a valve in said casing having a stem extending through said cap and said diaphragm, means for rigidly securing said diaphragm to said stem, means 100 for closing said valve, a hook removably secured to the inner end of said stem, and a fusible link having one end secured to the slotted end of said yoke and the opposite 105 end secured to said hook to hold said valve normally in open position.

In testimony whereof I affix my signature in presence of two witnesses.

WILLIAM HOWARD PAINE.
